(57) **CLAIM**

The ornamental design for a razor handle, as shown and
described.

DESCRIPTION

FIG. 1 is a front perspective view of a razor handle, showing
our new design;

FIG. 2 is a front view of the razor handle illustrated in FIG.
1;

FIG. 3 is a rear view of the razor handle illustrated in FIG.
1;

FIG. 4 is a left side view of the razor handle illustrated in
FIG. 1;

FIG. 5 is a right side view of the razor handle illustrated in
FIG. 1;

FIG. 6 is a top view of the razor handle illustrated in FIG.
1;

FIG. 7 is a bottom view of the razor handle illustrated in
FIG. 1; and,

FIG. 8 is a front perspective view of the razor handle
